UNITED STATES PATENT OFFICE.

CHARLES W. DAKE, OF CHICAGO, ILLINOIS, ASSIGNOR TO FYLE-NATIONAL ELECTRIC HEADLIGHT COMPANY, OF CHICAGO, ILLINOIS, A CORPORATION OF NEW JERSEY.

BRACKET FOR LOCOMOTIVE-HEADLIGHTS.

1,138,848.

Specification of Letters Patent. Patented May 11, 1915.

Application filed December 30, 1914. Serial No. 879,639.

To all whom it may concern:

Be it known that I, CHARLES W. DAKE, a citizen of the United States, residing at Chicago, in the county of Cook and State of Illinois, have invented a certain new and useful Improvement in Brackets for Locomotive-Headlights, of which the following is a specification.

My invention relates to improvements in brackets for electric headlights and the like and has for one object to provide a new and improved form of light bracket which will support a source of light and which will enable it to be conveniently and accurately 15 adjusted in position to focus it in the reflector.

Other objects of the invention will develop in the course of the specification.

The invention, therefore, is illustrated in 20 the accompanying drawings, wherein—

Figure 1 is a section through a head case showing the electric bracket in elevation; Fig. 2 is a rear view of the lamp bracket adjusting means with parts broken away; Fig. 3 is a front view of the same; Fig. 4 is a 25 section on the line 4—4 of Fig. 3; Fig. 5 is a section on the line 5—5 of Fig. 3 with parts removed; Figs. 6 and 7 are sections on the line 6—6 and 7—7 of Fig. 2.

Like parts are indicated by like letters 30 throughout the several figures.

A is a platform or base upon which is mounted the headlight case A¹ having a hinged rear door A² and a front glass A³. 35 A parabolic mirror or reflector A⁴ is contained within the case and held in position by any suitable means here indicated as screws A⁵ engaging the ring A⁶ in the case. This parabolic reflector is provided with a 40 central aperture at its bottom as indicated.

B is a foundation block resting on the base A. It has rigidly mounted thereon a bracket base B¹. This bracket base B¹ has upwardly projecting from it a supporting 45 arm B² which extends rearwardly and upwardly from the base and which carries a rectangular frame B³.

B⁴, B⁵ are arms projecting forwardly from the rectangular frame, B³, and B⁶ are curved 50 reflector contacting surfaces adapting to engage and rest against the outer surface of the reflector to insure a proper positioning of the bracket with respect to the reflector. The parts above described are all of them fixed in position and placed in such rigid

fixed position when the device is assembled. With this fixed bracket it is necessary to have means for adjusting the light source which in the present instance I have shown as an incandescent filament in three directions to get the source of light at the proper focal point in the reflector. It must be possible to move the source of light up and down in a vertical plane. It must be possible to move it from side to side in a horizontal plane and also to move it longitudinally along the axis of the reflector and I provide means for giving the electric lamp socket all these movements.

C, C are V-shaped grooved or bearing 70 slots in the rectangular frame B³ partially formed by a removable cover plate C¹. Slidably mounted and free to slide vertically in these slots is a rectangular plate or carriage C² having a sharpened V-shaped 75 edge to engage these slots.

C³ is a screw-threaded boss at the top of the frame B³ and C⁴ a screw-threaded boss at the top of the frame C².

C⁵ is a screw having a right-hand thread 80 in threaded engagement with the boss C³ and a left-handed thread in engagement with the boss C⁴ so that a rotation of the screw will give, owing to the fact that the screw moves with respect to both frames, a movement to 85 the slidable frame equal to the sum total of the two respective movements.

C⁶ is a thumb nut for manipulation of the screw and C⁷ a lock nut screw threaded on the screw. 90

It will be noted that the rectangular frame B³ has a front web C⁸ apertured to leave a substantially square hole having curved corners.

D, D are inclined bearing surfaces on the 95 frame C². In engagement with these two inclined bearing surfaces is a rectangular plate D¹ which plate is free to slide along these bearing surfaces in a horizontal direction being guided partially by them, partially by the plate C² and partially by the web C⁸.

D², D³ are screw-threaded bosses on the plates C², D¹ engaged by a similar screw D⁴ having a right-hand thread and left-hand 105 thread to engage said bosses, a thumb piece D⁵ and a lock nut D⁶ in a horizontal direction.

E is a bearing ring rigidly mounted in 110 the plate D¹.

- E¹ is a sleeve slidable in the bearing ring E and containing a standard electric light socket E².
- E³, E⁴ are screw-threaded bosses on the 5 sleeve E¹ and the plate D³.
- E⁵ is a screw having right and left-hand threads in engagement with said bosses and provided with a thumb piece and lock nut E⁷.
- 10 F is an electric light bulb with a filament F¹ in engagement with the socket E².
- F² are electric light wires passing out from the rear end of the socket and sleeve E² through the insulating sleeve F⁴ and 15 passing through the wall of the headlight housing to any source of electrical power not here illustrated.
- I claim:
1. A bracket for locomotive headlights and the like comprising a fixed supporting member, means carried thereby for supporting an electric light and for moving it in a horizontal and in a vertical plane along three lines in such planes each perpendicular to 25 the others.
  2. A bracket for locomotive headlights and the like comprising a fixed supporting member, separate means carried thereby for supporting an electric light and for moving it 30 in a horizontal and in a vertical plane.
  3. A bracket for locomotive headlights and the like comprising a fixed supporting member, separate means carried thereby for supporting an electric light and for moving it 35 in a horizontal and in a vertical plane along three lines in such planes each perpendicular to the others.
  4. A support for locomotive headlights and the like comprising a fixed bracket, a carriage mounted thereon, means for moving it along a vertical line, a slide in said carriage and means for moving it with respect to said carriage along a horizontal line, a light supporting sleeve in said slide and 40 means for moving it along a horizontal line perpendicular to the line of movement of the slide.
  5. A support for locomotive headlights and the like comprising a fixed bracket, a carriage mounted thereon, a slide mounted in said carriage for movement at 45 right angles to the line of movement thereof, a light supporting member mounted in said slide for movement at right angles to the line of movement of both the carriage and the slide.
  6. A support for locomotive headlights and the like comprising a fixed bracket, a carriage mounted for movement thereon, a slide 50 mounted in said carriage for movement at right angles to the line of movement thereof, a light supporting member mounted in said slide for movement at right angles to the line of movement of both the carriage and the slide.
- said slide for movement at right angles to the line of movement of both the carriage and the slide and means for positioning and locking each of said movable members with respect to the one in which it is directly mounted.
7. A support for locomotive headlights and the like comprising a fixed bracket and separate means carried thereby for supporting and moving the source of light in three intersecting planes.
8. A support for locomotive headlights and the like comprising a fixed bracket and means mounted thereon for adjusting the light source in three intersecting lines each of them perpendicular to the others.
9. A support for locomotive headlights and the like comprising a fixed bracket and separate means mounted thereon for adjusting the light source in three intersecting lines each of them perpendicular to the others.
10. A support for locomotive headlights and the like comprising a fixed bracket, means for supporting an electric light and for moving it in a horizontal plane along two lines perpendicular one to the other and means for moving it along a vertical line perpendicular to the two horizontal lines.
11. A support for locomotive headlights and the like comprising a fixed bracket, means for supporting an electric light and for moving it in a horizontal plane along two lines perpendicular one to the other and means for moving it along a vertical line perpendicular to the two horizontal lines, said means comprising a series of separate sliding members and means for moving them.
12. A support for locomotive headlights and the like comprising a fixed bracket, means for supporting an electric light and for moving it in a horizontal plane along two lines perpendicular one to the other and means for moving it along a vertical line perpendicular to the two horizontal lines, said means comprising a series of separate sliding members and means for moving them and locking them in position.
13. In a locomotive headlight the combination with a parabolic reflector of a light supporting bracket, means comprising three separate curved surfaces on said bracket for engaging the outside of the reflector adjacent its focus and holding it in position with respect to the bracket.
- In testimony whereof, I affix my signature in the presence of two witnesses this 23rd day of December, 1914.
- CHARLES W. DAKE.
